US00D478305S

(12) **United States Design Patent** (10) Patent No.: **US D478,305 S**
Kern (45) Date of Patent: **** Aug. 12, 2003**

(54) **WHEEL**

(75) Inventor: **Steven J. Kern**, Palatine, IL (US)

(73) Assignee: **GB Automotive Products, Inc.**, Hawthorne, CA (US)

(**) Term: **14 Years**

(21) Appl. No.: **29/166,881**

(22) Filed: **Sep. 5, 2002**

(51) LOC (7) Cl. **12-16**

(52) U.S. Cl. **D12/209**

(58) Field of Search **D12/204-211; 301/37.101, 64.101, 65**

(57) **CLAIM**

The ornamental design for a wheel, as shown and described.

DESCRIPTION

FIG. 1 is a front perspective view of the wheel showing my new design;

FIG. 2 is a front elevational view of the wheel showing my new design; and,

FIG. 3 is a side elevational view thereof, it being understood that the opposite side is a mirror image thereof.

1 Claim, 2 Drawing Sheets

Fig. 1
